UNITED STATES PATENT OFFICE.

GEORGE A. LOCKE, OF GLEN COVE, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed February 5, 1924. Serial No. 690,704.

This invention relates to signaling systems and particularly to the apparatus and circuits employed for high speed transmission of signal impulses which are controlled by a perforated message tape. It has recently been proposed to increase very greatly the speed of signaling over ocean cables by inductively loading the cable by means of a surrounding sheath of a newly discovered alloy of iron and nickel having very high permeability at low magnetizing forces. The signaling frequencies obtainable with such a cable are far above the speed of operation of the Wheatstone type of transmitter as commonly used for submarine cable transmission which is limited in its speed of satisfactory operation due to the inertia of its reciprocating parts and the unavoidable vibration of its moving parts. To avoid these limitations it has been proposed to employ a pneumatic transmitter of the type disclosed in a copending application of Allison A. Clokey, Serial No. 680,815, filed December 15, 1923. Such a transmitter is capable of much higher operating speeds than have been possible heretofore, its speed of operation being limited by the variable length of signals which sometimes occur due to change in air pressure as a result of previous signals sent.

It is the object of the present invention to correct the signals of varying length and transmit them to the line as corresponding signals of uniform length.

To accomplish this object, the invention contemplates storing the impulses received from the transmitting mechanism and subsequently transmitting to the line corresponding impulses of uniform length. The invention is described in detail in the following specification and reference is made to the accompanying drawing in which Figs. 1 and 2, taken together, with Fig. 2 at the right, disclose a transmitting system in accordance with the invention, and Fig. 3 shows the brush arrangement employed on one of the transmitting faces of the rotary distributor.

Referring to the drawing, the transmitter T which is described in detail in the above mentioned application, consists essentially of a pair of diaphragms 50 and 51 enclosing suitable air chambers which communicate as shown, with a reservoir 52 maintained at

a constant pressure. These air chambers also communicate with openings in a platen (not shown) over which the perforated message tape is passed, the openings being arranged so as to be in alignment respectively with the dot and dash perforations in the tape. The diaphragm 50 is connected through a resistance 54 to the negative terminal of a grounded battery 55. In a similar manner diaphragm 51 is connected through a resistance 56 to the positive terminal of the grounded battery 57. A contact member 58 is adapted to engage diaphragm 50 when the latter is flexed outward and a similar contact 59 is arranged to engage diaphragm 51. These contact members are connected to the common ring 60 of the receiving section A of a rotary distributor, the commutator of which is shown developed. By means of a brush 61, the common ring is connected in order with segments 1 to 40. The distributor and the tape feeding mechanism are positively driven by the same motor and the number of segments is made to correspond with the number of teeth in the tape feeding mechanism so that brush 61 passes to another segment each time the tape is advanced one step. The segments 1 to 40 are divided into four groups, the segments of which are connected in common and to the windings of a pair of polarized relays. Thus, segments 1, 5, 9, etc., are connected in multiple and to the windings 62 and 63 of the first or left-hand group of relays. Segments 2, 6, 10, etc., are connected in multiple and to the windings 64 and 65 of the second group of relays. Segments 3, 7, 11, etc., are in like manner connected to the windings 66 and 67 of the third group of relays, while segments 4, 8, 12, etc., are connected to the windings 68 and 69 of the fourth or right-hand group of relays.

The restoring section B of the distributor comprises a common ring 70 permanently connected to a grounded source of energy 71 and a group of 40 restoring segments of equal length which are adapted to be connected to ring 70 by means of brush 72. These segments are divided into four groups in the same manner as are the receiving segments, the group containing segments 1, 5, 9, etc., being connected to windings 74 and 76 of the first group of relays, the group containing segments 2, 6, 10, etc., being con-

5 nected to the windings 77 and 78 of the second group of relays, the group containing segments 3, 7, 11, etc., being connected to the windings 79 and 80 of the third group of relays and the group containing segments 4, 8, 12, etc., being connected to the windings 81 and 82 of the fourth or last group of relays.

10 The sending section C of the distributor consists of a common ring 85 and a set of 40 segments of equal length which are connected to the ring 85 in order by means of the brush 86. These segments are connected together in four groups in the same manner 15 as the segments of the receiving and restoring sections, segments 1, 5, 9, etc., being connected to the armature 87 of the lower relay of group 1, segments 2, 6, 10, etc., being connected to the armature 88 of the lower relay 20 of group 2, segments 3, 7, 11, etc., being connected to the armature 89 of the lower relay of group 3, and segments 4, 8, 12, etc., being connected to the armature 90 of the lower relay of group 4.

25 In order to control the time during which the current impulses are impressed upon the line, there is provided on the distributor a curbing section D consisting of a common ring 91 permanently connected to the common ring 85 of the sending section, a common ring 92 which is permanently connected to ground, a common ring 93 which is connected to the line or cable 94, and a set of 30 40 segments corresponding to the segments in the other sections of the distributor. These latter segments are divided into two groups each of the alternate segments being 35 connected together electrically to form a group of odd segments and a group of even segments. These segments are connected to ring 91 by means of brush 95, to ring 92 by means of brush 96 and to ring 93 by means of brush 97. As is shown more clearly in Fig. 3, brushes 95 and 96 are mounted in 40 fixed relation with respect to each other and in such a manner that when one brush is just entering upon an even segment, the other brush is just entering upon an odd segment. Brush 97, on the other hand, is 45 made adjustable so that it is possible to regulate the time interval during which the signal impulses are impressed upon the line.

50 A separate source of energy for the line current is provided for each set of relays. 55 For the relays of group 1 the source of energy comprises batteries 100 and 101 connected in series. The positive pole of battery 100 is connected through resistance 102 to contact 105 of the upper relay of the 60 group and to contact 106 of the lower relay of the group. Similarly, the negative pole of battery 101 is connected to contact members 103 and 104. The common point of batteries 100 and 101 is connected through winding 107 to armature 108 of the upper

relay and through the winding 109 to armature 87 of the lower relay in order to provide a locking winding. For the second group of relays, the positive pole of battery 110 is connected through resistance 111 to contacts 116 and 117 while the negative terminal of battery 114 is connected through resistance 115 to contact members 112 and 113. The common point of batteries 110 and 114 is connected through winding 118 to the armature 119 of the upper relay and through winding 120 to the armature 88 of the lower relay. In the third group of relays the positive terminal of battery 121 is connected through resistance 122 to contacts 127 and 128. The negative terminal of battery 125 is connected through resistance 126 to contact members 123 and 124. The common point of batteries 121 and 125 is connected through winding 129 to the armature 130 of the upper relay and through winding 131 to the armature 89 of the lower relay. In the fourth group of relays, the positive terminal of battery 132 is connected through resistance 133 to contact members 138 and 139 and the negative terminal of the battery 136 is connected through resistance 137 to contact members 134 and 135. The common point of batteries 132 and 136 is connected through winding 140 to armature 141 of the upper relay of this group and through winding 142 to armature 90 of the lower relay of this group. For the purpose of polarizing the relays, the grounded source of energy 143 is connected serially through the windings 144 to 151, inclusive and thence to ground.

55 In the operation of the system, the brushes 61, 72 and 86 are so positioned with respect to each other that when brush 61 is just passing upon segment 1, the restoring brush 72 is just passing upon segment 2 and the sending brush 86 is just passing upon segment 3. Thus, while the receiving brush is passing over segment 1, the restoring brush is passing over segment 2 and removes the previous signal set up on this group, returning the relays to zero position in a manner to be explained hereinafter. At the same time the sending brush is passing over segment 3 and is transmitting the signal that has been set up on relay group 3. The operation thus takes place in four distinct steps. In the first step, group 1 receives the signal from the transmitter, group 2 is restored to its zero position and group 3 is transmitting the signal previously received. During the second step group 2 receives, group 3 restores and group 4 transmits. During the third step, group 3 receives, group 4 restores and group 1 transmits. During the fourth step, group 4 receives, group 1 restores and group 2 transmits. In this method of transmission a signal is received in one step and during the next step

no action takes place. During the third step the signal is transmitted, while during the fourth step the relay is returned to its zero position. By this means false signaling, due to chattering of the relay armatures is eliminated and the signals transmitted to the line are of uniform length.

Let it be assumed, as shown, that a dot perforation is in alignment with the opening in the platen so that diaphragm 51 will be separated from contact 59 but diaphragm 50 will engage contact 58. Current will then flow from the grounded source of energy 55 through resistance 54, diaphragm 50, contact 58 to the common ring 60 of the receiving section of the distributor. With brush 61 in engagement with segment 1 of this section, a circuit will be completed through windings 62 and 63 of the first group of relays and to ground, thus energizing these relays. Since these windings are connected in opposite directions the armatures will be moved in opposite directions as shown and a circuit will be set up in readiness to subsequently transmit impulses to the line.

At the same time brush 72 will be resting upon segment 2 of restoring section B, thus completing the circuit from grounded source of energy 71, through common ring 70, brush 72, segment 2, windings 77 and 78 in the second group of relays to ground. Since the windings 77 and 78 are connected in the same direction, armatures 88 and 119 will be operated in the same direction, thus restoring the signal which had been previously set up on this group of relays and returning the armature to the zero position. Also, at the same time brush 86 will be passing over segment 3 of transmitting section C, thus permitting the transmission of the signal which has previously been set up on the third group of relays. With the armatures of this group operated in the positions shown, the negative terminal of battery 125 will be connected through resistance 126, contact 123 and armature 130 to ground and the positive terminal of battery 121 will be connected through resistance 122, contact 128, armature 89 to segment 3 of transmitting section C and thence by brush 86 and ring 85 to the common ring 91 of curbing section D. As brush 86 just starts to pass over transmitting segment 3, brush 95 will be just entering upon an odd segment and brush 96 will be just entering upon an even segment, while brush 97 with the adjustment as shown will be upon the midportion of an odd segment. The circuit will, therefore, be completed from ring 91 through brush 95 to segment 3, thence to segment 25, brush 97 and common ring 93 to the cable 94. By the time that brush 86 has reached the position on segment 3 shown, brush 97 will have passed from segment 25 to seg-

ment 26 and the cable will then be connected through brush 97 to segment 26 thence to an even segment 34, brush 96 and common ring 92 to ground. Therefore, during approximately the first 50% of the signaling interval battery will be impressed upon the cable and during the latter portion of the signaling interval the cable will be grounded. Obviously, by adjusting the position of brush 97 it is possible to vary the curbing from zero, where the signal is impressed upon the line during the entire interval, to 100%, where the cable is grounded during the entire interval. Referring to the first group of relays when they are energized by current flowing through windings 62 and 63 to ground, the armatures take up the positions shown and holding circuits are provided as follows: From the negative terminal of battery 101 through resistance 99, contact 103, armature 108 to ground and thence through winding 107 to the positive terminal of battery 101. From the negative terminal of battery 100 through winding 109 of the lower relay, armature 87, contact 106, resistance 102 to the positive terminal of battery 100. Similar locking windings are provided for each group of relays, thus insuring positive operation with minimum chattering.

What is claimed is:

1. In a signaling system an automatic transmitter, a distributor adapted to receive current impulses directly from said transmitter, and means cooperating with the distributor to receive, store and transmit to the line current impulses of uniform length corresponding to the impulses received by the distributor.

2. In a signaling system a transmitter controlled by a message tape, a rotary distributor driven in synchronism with the tape feeding mechanism, a plurality of pairs of polarized relays cooperating with the distributor to store up current impulses of variable length received directly from the distributor and transmit to the line corresponding current impulses of uniform length.

3. In a signaling system an automatic transmitter, a plurality of groups of polarized relays and a rotary distributor comprising means for distributing to the relays current impulses received directly from the transmitter, and additional means for distributing to the line current impulses generated by the relays corresponding to the impulses received from the transmitter.

4. In a signaling system an automatic transmitter, a plurality of groups of polarized relays and a rotary distributor comprising means for distributing current impulses from the transmitter to the relays, additional means for distributing to the line current impulses generated by the relays

corresponding to the impulses received from the transmitter, and additional means for restoring said relays to their zero position.

5. In a signaling system an automatic transmitter under the control of a perforated message tape, a rotary distributor comprising receiving, sending and restoring sections, and a plurality of pairs of polarized relays having windings under the control of current impulses transmitted over the receiving section of said distributor and having contact members associated with suitable sources of energy to subsequently regenerate current impulses corresponding to said transmitted impulses, said sending sections of the distributor being adapted to distribute the regenerated impulses to the line in their proper sequence.

6. In a signaling system an automatic transmitter, a plurality of groups of polarized relays and a rotary distributor comprising means for sequentially operating said relay groups in accordance with the current impulses transmitted to regenerate corresponding current impulses, means for distributing said regenerated current impulses, and additional means for restoring said relay groups to their zero position.

7. In a signaling system an automatic transmitter adapted to transmit positive, negative and zero impulses, and means controlled by said impulses and comprising a rotary distributor and a plurality of pairs of polarized relays for subsequently generating corresponding current impulses of uniform length, and distributing said generated impulses to the line in the same sequence as the impulses were received from the transmitter, said distributor having a receiving section adapted to receive impulses from the transmitter and distribute them in order to the various pair of relays, a sending section adapted to transmit to the line current impulses generated by the relays and corresponding to the impulses received from the transmitter, and a restoring section for restoring the relays to their normal positions.

8. In a signaling system an automatic transmitter, a rotary distributor comprising receiving, sending and restoring sections, each of said sections including a common ring and a plurality of segments divided into a plurality of segmental groups, the segments of each group being connected in multiple a pair of polarized relays corresponding to each of said segmental groups, each of said relays including an operating winding associated with its corresponding group of segments in the receiving section, a restoring winding associated with its corresponding group of segments in the restoring section, and contact members associated with its corresponding group of segments in the sending section.

9. In a signaling system an automatic

transmitter for generating current impulses in accordance with the perforations in a message tape, a plurality of groups of polarized relays, means for operating said groups of relays sequentially in accordance with the impulses transmitted, means for generating and transmitting to the line current impulses of uniform length corresponding to the impulses received from the transmitter and means for varying the time intervals 75 during which such generated impulses are impressed upon the line.

10. A telegraph signaling system comprising an automatic transmitter, a distributor for receiving current impulses from said transmitter, and a plurality of groups of relays cooperating with the distributor to transmit, to the line, current impulses of uniform length corresponding to the impulses received by the distributor, the relays of a group being controlled by current impulses received by the distributor, and cooperating to form the current impulses of uniform length distributed to the line.

11. A telegraph signaling system, comprising an automatic transmitter, a distributor for receiving current impulses from said transmitter and a plurality of groups of relays cooperating with the distributor to transmit, to the line, current impulses of uniform length corresponding to the impulses received by the distributor, each of said groups comprising two relays and the relays of each group having operating windings connected so as to be energized simultaneously by current impulses received by the distributor, and cooperating to form the current impulses of uniform length distributed to the line.

12. A telegraph signaling system, comprising an automatic transmitter, a distributor for receiving current impulses from said transmitter, and a plurality of groups of relays cooperating with the distributor to transmit, to the line, current impulses of uniform length corresponding to the impulses received by the distributor, the relays of a group being controlled by current impulses received by the distributor and cooperating to form the current impulses of uniform length distributed to the line, each of said relays having a polarizing winding all of which are connected in series to a source of current.

13. A telegraph signaling system, comprising an automatic transmitter, a distributor for receiving current impulses from said transmitter, and a plurality of groups of relays cooperating with the distributor to transmit, to the line, current 125 impulses of uniform length corresponding to the impulses received by the distributor, the relays of a group being controlled by current impulses received by the distributor and cooperating to form the current im- 130

5 pulses of uniform length distributed to the line, each of said relays having a polarizing winding, a locking winding, and a storing winding, the polarizing windings of all the relays being connected in series to a source of current.

14. A telegraph signaling system, comprising an automatic transmitter, a distributor for receiving current impulses from 10 said transmitter, and a plurality of groups of relays cooperating with the distributor to transmit, to the line, current impulses of uniform length corresponding to the impulses received by the distributor, the relays of a group being controlled by current impulses received by the distributor and 15 cooperating to form the current impulses of uniform length distributed to the line, the relays of each group being so connected 20 to the distributor that they may be controlled by received current impulses of either positive or negative polarity.

15. A telegraph signaling system comprising an automatic transmitter, a distributor for receiving current impulses from 25 said transmitter, and a plurality of groups of relays cooperating with the distributor to transmit, to the line, current impulses of uniform length corresponding to the impulses received by the distributor, the relays of a group being controlled by current impulses received by the distributor and 30 cooperating to form the current impulses of uniform length distributed to the line, the contacts of the relays within a group being 35 so interconnected that during the sending to the line of an impulse generated by said relays the impulse sent is transmitted through contacts of each of the relays forming 40 the group.

16. A telegraph signaling system comprising an automatic transmitter, a rotary distributor, an outgoing line, a source of signaling current for said line, a plurality of polarized relays cooperating with said distributor to receive and store current impulses 45 received from said transmitter through said distributor, and subsequently cooperating with said distributor to impress current impulses of uniform length, and corresponding to the received impulses, upon said line from said source, through a circuit including said source, a contact of one of said relays, said distributor and said line, said relays operating in distinct steps determined by said distributor to permit of certain delay between the receipt by said 50 relays of impulses from said transmitter and the transmission of impulses to said line.

17. A telegraph signaling system comprising an automatic transmitter, an outgoing line, a source of signaling current for said line, a rotary distributor having receiving segments and transmitting segments, a plurality of groups of polarized relays 60 cooperating with said distributor to receive and store current impulses received from said transmitter through said receiving segments, and cooperating with said transmitting segments to impress, upon said line, current impulses from said source of uniform length and corresponding to the received impulses, said transmitting segments at the time of transmission of the signal to said line being included between said 75 line and said source.

18. A telegraph signaling system comprising an automatic transmitter, an outgoing line, a source of signaling current for said line, a rotary distributor having 80 receiving segments, transmitting segments, and curbing segments, a plurality of groups of polarized relays cooperating with said distributor to receive and store current impulses received from said transmitter 85 through said receiving segments, and cooperating with said transmitting segments to impress upon said line, current impulses from said source of uniform length and corresponding to the received impulses, said 90 transmitting segments at the time of transmission of the signal to said line being included between said line and source.

19. A telegraph signaling system comprising an automatic transmitter, a distributor for receiving current impulses from the transmitter, and four groups of polarized relays to store the current impulses received by the distributor and to generate current impulses of uniform length 100 corresponding to the received impulses and cooperating with the distributor to distribute the generated impulses to the line, said relay groups operating in four distinct steps determined by the distributor, whereby during each step a group is receiving, another group is restoring, a third group is transmitting and a fourth group is storing and during successive steps different groups are receiving, restoring and transmitting 105 so that any one group is receiving, storing, transmitting and being restored during the series of four steps.

In witness whereof, I hereunto subscribe my name this 4th day of February A. D., 115 1924.

GEORGE A. LOCKE.
